UNITED STATES PATENT OFFICE.

JOHN G. MILLER, OF CHAMPAIGN, ILLINOIS.

HARNESS-TUG SLIDE.

SPECIFICATION forming part of Letters Patent No. 293,903, dated February 19, 1884.

Application filed July 12, 1883. (No model.)

To all whom it may concern:

Be it known that I, JOHN G. MILLER, a citizen of the United States, residing at Champaign, in the county of Champaign and State of Illinois, have invented certain new and useful Improvements in Harness-Tug Slides; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a vertical sectional view of my invention. Fig. 2 is a front view, and Fig. 3 is a detail view.

This invention has relation to harness-tug slides; and it consists in the construction and novel arrangement of the rack-plate on the saddle-flap and the adjustable metallic loops in connection therewith, the metallic tug-slide having end loops and center pin to engage the back-band, and slotted or recessed in its inner face to accommodate the rack-plate, all as hereinafter set forth.

In the accompanying drawings, the letter *a* designates the saddle-flap, and *b* the back-band connected thereto.

On the outer face of the flap *a* is secured a rack-plate, *c*, the rack-face of which is turned inward or toward the flap. The rack-plate is secured to the flap by rivets *d*, passing through its ends, and on the rack-plate are the adjustable metallic loops *e*, which are centrally notched at *g*, to engage the rack-plate and prevent transverse play when the back-band *b* is in position, having been passed through said loops.

H indicates the metallic tug-slide, having 40 the transverse opening or bearing *k*, through which the tug passes, and the end loops, *l*, through which the back-band is passed in connecting the tug-slide thereto. Flanges *m* of the slide guard the edges of the back-band, and a 45 center stud, *p*, projecting from the outer or convex face of the slide, is designed to engage a perforation, *r*, of the back-band after the slide has been adjusted in position.

The inner face of the slide is designed to be 50 in contact with the saddle-flap; and in order to provide for the accommodation of the rack-plate when the slide is adjusted to a low position, a slot or recess, *z*, is made in the inner face of the slide, said slot or recess extending 55 longitudinally, as indicated in the drawings.

The adjustment of the tug-slide is mainly governed by the rack-plate on the saddle-flap and the adjustable loop, which is fixed in position with reference to said rack-plate when 60 the back-band has been passed through said loop.

Having described this invention, what I claim, and desire to secure by Letters Patent, is—

The combination, with the rack-plate on the saddle-flap, of the adjustable metallic loops, the metallic tug-slide having end loops and center pin to engage the back-band, and slotted or recessed in its inner face, to accommodate the rack-plate, substantially as specified.

In testimony whereof I affix my signature in presence of two witnesses.

JOHN G. MILLER.
